(57) **CLAIM**

The ornamental design for a pet harness, as shown and described.

DESCRIPTION

FIG. 1 is a top perspective view of a pet harness showing my new design;

FIG. 2 is a bottom perspective view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a rear elevation view thereof;

FIG. 8 is a front elevation view thereof;

FIG. 9 is an enlarged view of detail “9” shown in FIG. 1;

FIG. 10 is an enlarged view of detail “10” shown in FIG. 1;

FIG. 11 is an enlarged view of detail “11” shown in FIG. 1;

FIG. 12 is an enlarged view of detail “12” shown in FIG. 5; and,

FIG. 13 is an enlarged view of detail “13” shown in FIG. 7.

The dash-dash broken lines in the drawings depict portions of the pet harness that form no part of the claimed design. The dot-dash broken lines represent boundaries of the enlarged portion and form no part of the claimed design.

1 Claim, 13 Drawing Sheets
